United States Patent

Des. 237,172
Patented Oct. 14, 1975

237,172

SWIVELING, ROTARY, CARD HOLDER

Manfred K. Hegemann, Nyack, N.Y., assignor to Zephyr
American Corporation, Secaucus, N.J.

Filed Oct. 9, 1973, Ser. No. 404,272

Term of patent 14 years

Int. Cl. D19—02

U.S. Cl. D19—76

FIG. 1

FIG. 2

FIG. 4

FIG. 3

FIG. 5

FIG. 1 is a front elevational view of a swiveling, rotary, card holder showing my new design;

FIG. 2 is a right side elevational view;

FIG. 3 is a left side elevational view;

FIG. 4 is a top plan view; and

FIG. 5 is a rear elevational view.

I claim:

The ornamental design for a swiveling, rotary, card holder, as shown and described.
